UNITED STATES PATENT OFFICE

JOSEPH D. McNUTT, OF NEW HAVEN, CONNECTICUT, ASSIGNOR, BY MESNE ASSIGNMENTS, TO WINCHESTER REPEATING ARMS CO., OF NEW HAVEN, CONNECTICUT, A CORPORATION OF DELAWARE

PRIMING MIXTURE

No Drawing. Application filed March 31, 1927. Serial No. 180,080.

My invention relates to an improvement in priming mixtures, the object being to produce a priming mixture of such a character that it will leave no corrosive residuum to act on the material of the barrel of the firearm in which it is used, and which will not deteriorate in storage.

With these ends in view, my invention consists in a priming mixture comprising a metallic nitrate, a metallic sulfid, a metallic fulminate, an organic nitro derivative and a chemically-basic stabilizing agent.

In carrying out my invention, I employ the above-named ingredients in substantially the following proportions, dependent upon the specific use to be made of the mixture:

475 parts of mercury fulminate, carrying 16% water; 240 parts of barium nitrate; 255 parts of antimony sulfid; 30 parts of trinitrotoluene; and $\frac{1}{2}$ to 2 parts of diphenylamin or calcium carbonate.

In proceeding to make the mixture, the barium nitrate and the diphenylamin are intimately mixed. The required quantity of barium nitrate and stabilizer so mixed is then weighed out, together with the required quantity of antimony sulfid, and these are mixed in any convenient manner. A small amount of a solution of gum in water is now incorporated with the mixture; the required quantities of mercury fulminate and trinitrotoluol are added thereto; and the whole is thoroughly mixed together. The resultant mixture is then ready for immediate use in the manufacture of primers.

I claim:

1. A composition for initial igniters, comprising mercury fulminate, barium nitrate, antimony sulfid, trinitrotoluene and diphenylamin.

2. A composition for initial igniters, comprising 475 parts of mercury fulminate carrying 16% water, 240 parts barium nitrate, 255 parts antimony sulfid, 30 parts trinitrotoluene and $\frac{1}{2}$ to 2 parts of a chemically-basic stabilizing agent.

3. A composition for initial igniters comprising 475 parts of mercury fulminate carrying 16 percent of water, 240 parts barium nitrate, 255 parts antimony sulphide, 30 parts

trinitrotoluene and $\frac{1}{2}$ to 2 parts diphenylamin.

In testimony whereof, I have signed this specification.
